UNITED STATES PATENT OFFICE.

THOMAS M. FLETCHER, OF FONTANA, WISCONSIN, ASSIGNEE TO THE Q. R. S. MUSIC COMPANY, OF CHICAGO, ILLINOIS, A CORPORATION OF ILLINOIS.

MUSIC-ROLL TERMINAL AND CLASP.

Application filed June 12, 1922. Serial No. 567,575.

The purpose of this invention is to provide a terminal member for a music roll, adapted to normally retain the roll snugly wound on the spool. It consists in the elements and features of construction shown and described, as indicated in the claims.

In the drawings:—

Figure 1 is a perspective view of a music roll equipped with this invention with the end portions unwound for a short distance for showing the terminal clasp.

Figure 2 is a transverse section of such a roll fully wound with clasp operating for holding it snugly wound.

Figure 3 is a detail section longitudinal with respect to the music roll sheet through the terminal lug and the clasp device, showing the several parts or layers magnified in section for showing the manner of securing the spring clasp in and with respect to the said lug.

It is well known and familiar experience that music rolls tend to become unwound or to become loosely wound on their spools, and thereby the outer or terminal portions are liable to become rapidly deteriorated in handling, and particularly in thrusting into and withdrawing them from the containing boxes. To overcome this defect I provide a spring clasp member connected with and preferably forming a substantial part of the terminal lug, which is normally coiled so as to embrace the wound roll closely, being elastically flexible so that it may be readily uncoiled to unwind the roll, and so that it normally comes into clamping relation to the roll as the latter is wound onto the spool.

As shown in the drawing, and as preferably constructed, between the two layers, 2, 2, of the terminal lug, which are of any suitable tough and flexible sheet material and which are attached in the usual manner by gluing them onto the opposite surfaces of the music roll sheet a strip of elastically flexible material, which may be thin steel spring, as a watch spring, or preferably, as intended to be indicated by the drawings, a strip of celluloid, shown at 3, which is normally coiled somewhat less in diameter than the diameter of the wound roll, so as to tend to clasp the latter rather closely, as seen in Figure 2. This strip of elastic material reinforces the terminal lug and extends beyond

the customary eyelet, 4, therein which is provided for engaging the winding pin of the take-up roll; and when said elastic strip is of the width shown in the drawing, the eyelet, 4, passes through it and assists in securing it in and to the terminal lug, 2, 2.

In use the operator takes hold of the terminal lug in the usual manner for starting the unwinding of the note sheet from the spool and immediately unhooks or unclasps the clasp, 3, and hooks the clasp into the round take-up roll in the groove in which the winding pin is situated; and holding the clasp in the groove while the roll revolves, the take-up winding pin as it comes around will engage the eyelet, and thus the device, besides accomplishing its primary purpose, facilitates the initial engagement of the note sheet with the take-up roll.

In rewinding, the operator, as usual, holds his hand lightly upon the music roll to cause the note sheet to be wound snugly, and at the end of the re-winding the note sheet becomes disengaged in the usual way from the take-up pin of the take-up roll, and as the end is drawn onto the music roll, the clasp normally becomes engaged around the roll, holding it snugly wound.

I claim:—

1. A music roll for automatic players; having a terminal lug for engagement of the take-up roll of the player provided with an elastic extension rigidly joined to and continuing integrally from its juncture with said lug, adapted to coil elastically around the roll when the latter is wound to the end thereof on the spool.

2. A spooled note sheet for automatic players having a terminal for engagement of the take-up roll of the player, provided with a spring which is in rigid conjunction with said terminal along an extent of the latter which is flexed about the roll in completing the winding of the note sheet on the spool and which protrudes in coil form beyond the end of said terminal which tends to coil elastically around the roll when the note sheet is wound on the spool.

3. In the construction defined in claim 1, foregoing, the terminal comprising two layers of sheet material adherent to the opposite sides of the note sheet extending there beyond and adherent to each other, the ex-

tension being an elastically-flexible strip normally coiled for embracing the roll and means securing the same closely enclosed between said two layers of the terminal lug.

5 4. In the construction defined in claim 1, foregoing, the extension member being an elastically flexible strip secured to the lug

for extending beyond the engagement of the latter with the take-up roll to the extent at least one-half the circumference of the roll. 16

In testimony whereof, I have hereunto set my hand at Chicago, Illinois, this 9th day of June, 1922.

THOMAS M. PLETCHER.
